CRACKER HOLDER OR SIMILAR ARTICLE

Arthur V. Knox, Phoenix, Ariz.

Application June 13, 1950, Serial No. 10,504

Term of patent 14 years

(Cl. D44—10)

To all whom it may concern:

Be it known, that I, Arthur V. Knox, a citizen of the United States, residing at Phoenix, in the county of Maricopa and State of Arizona, have invented a new, original and ornamental Design for a Cracker Holder or Similar Article, of which the following is a specification, reference being had to the accompanying drawings, forming a part thereof.

I claim:

The ornamental design for a cracker holder or similar article, as shown.

ARTHUR V. KNOX.
